GASOLINE STATION FUEL DISPENSER

Charles Everett Cook, 2470 Kingscliff Drive NE.,
Atlanta, Ga. 30345

Filed May 28, 1974, Ser. No. 473,549

Term of patent 14 years

Int. Cl. D20—02

U.S. Cl. D52—2 A

FIG. 4.

FIG. 5.

FIG. 1 is a side elevational view of a gasoline station fuel dispenser showing my new design, the opposite side being a mirror image thereto;

FIG. 2 is a top plan view thereof;

FIG. 3 is a bottom plan view thereof;

FIG. 4 is an enlarged partial left end perspective view thereof; and

FIG. 5 is an enlarged partial right end perspective view thereof.

I claim:

The ornamental design for a gasoline station fuel dispenser, as shown and described.
